CONTROL SYSTEM FOR FUEL BURNERS

Eugene Oscar Engels, Saginaw, Mich., assignor
to Baker Perkins Company, Inc., Saginaw,
Mich., a corporation of New York

Application November 1, 1935, Serial No. 47,804

2 Claims. (Cl. 110—163)

This invention relates to control systems for automatic gas or oil burners applied to furnaces, bake ovens, boilers and the like. It has for its object the provision of an improved mechanism for automatically controlling the burner and adjusting the draft of the furnace, whereby steady, clean combustion is obtained immediately upon igniting the burner in a cold furnace by preventing undesirable flashing back and explosive puffing, caused by intermittent extinguishing and re-ignition of the burner flame.

The invention by which I attain these objects in a furnace and an automatic fuel burner assembly comprises a motor-driven timing device, thermostatically or manually controlling, operatively connected to govern the ignition and operation of the burner and coincidentally to adjust the furnace draft control; the said control device connected and arranged to adjust the damper or other draft control for partial draft for a definite time interval before starting the fuel burner, then to put the burner into operation, and finally to move the damper gradually to its full open position, so that the burner flame is subjected to full draft only after the furnace and burner have reached a temperature high enough to insure steady complete combustion of the fuel.

By partially restricting the draft to the furnace when the burner is first ignited the velocity at which gases leave the burner is reduced so that the freshly started relatively cool flame can not be blown out or drawn away from the burner nozzle. Thus the intermittent extinguishing of the flame in a cold furnace, and consequent explosive ignition of the accumulated, unburned fuel-air mixture is prevented.

Further features and objects of my invention will be set forth in the following specification.

Referring to the drawing:

Fig. 1 is a diagrammatic side elevation of a furnace and fuel burner to which my improved control system is applied.

Fig. 2 is an enlarged side elevation, partly in section, of a stack damper and the burner control of Fig. 1 operatively connected thereto in accordance with the invention.

Fig. 3 is a top plan view of the burner control and damper of Fig. 2.

Fig. 1 shows diagrammatically a furnace 1 which may be utilized in any known way, for example, to heat a boiler, a dry kiln, or, more particularly to supply hot gases to a bake oven, as shown in my United States Patent No. 1,857,447, issued May 10, 1932. For purposes of illustration, the furnace includes, but does not show

any heat-absorbing system which may be interposed between the point of combustion and the point of discharge of waste gases.

A burner 2 of known form for burning gas, oil, or powdered fuel, is mounted in the wall of the furnace 1, and the spent products of combustion are discharged through a flue 3 to the atmosphere after their usable heat has been absorbed.

Referring more particularly to Figs. 2 and 3, the apparatus embodying my invention is operatively associated with a draft control damper 4 in the flue 3, and with the control circuit A of the fuel burner 2. Damper 4 is rotatably mounted in the walls of stack 3, to pivot from a fully closed to an open position. The damper is actuated by a lever arm 5 connected at its outer end to a connecting rod 6, which is journaled to a crank pin 7. Crank pin 7 is carried by and revolves with power output shaft 8 of an automatic motor-driven control device 9, of known form.

The motor control 9 may be connected in conventional manner to a high-low thermostatic control, or may be controlled by a manually operated switch in known manner. It is operable to revolve shaft 8 slowly one-half revolution in response to each energizing current impulse from the thermostatic or other control switch. A cam disk 10 is also fixed to shaft 8, and operatively engages a cam follower 11 mounted on the tripping arm of a switch 12. Switch 12 is connected to govern the burner control circuit A, so that the burner operates in response to the closing of the switch.

The operation of the control system is as follows:

With the burner off, and the furnace cold, damper 4 is in its closed position, as shown in broken lines in Fig. 2. The position of the operating linkage and the cam is also shown in broken lines. In response to an impulse from the thermostat or from a starting push button, the timing motor 9 goes into operation to rotate the cam disk 10 clockwise through a one-hundred-eighty degree arc, or one-half a revolution, in a predetermined length of time, for example, thirty to sixty seconds. As the shaft revolves, damper 4, through lever 5, connecting rod 6 and crank pin 7, is gradually swung toward its open position. During this time a slight draft of fresh air flows through the furnace, scavenging any explosive mixture or moving it out of the range of the burner flame so that it can not be ignited. When the damper is approximately half way open the leading edge of cam 10 engages the follower 11.

This closes the switch 12 and starts burner 1, which is ignited by the usual automatic ignition system (not illustrated). At this moment the cam, the damper, and the connecting linkage are 5 in the position shown in dotted lines in Fig. 2, and in solid lines in Fig. 3, and a period of fifteen seconds to half a minute has elapsed since the damper started to open. The timing motor 9 continues for an additional fifteen to thirty sec- 10 onds to rotate shaft 8 slowly through the re- mainder of its cycle of one-half revolution, gradu- ally swinging the damper 4 to its full open posi- tion, indicated in Fig. 1, and shown in solid lines in Fig. 3.

15 The above described cycle of operation pro- duces throughout the starting process the condi- tion most favorable for successful ignition and warming up of the burner and furnace. It is a common disadvantage of the ordinary oil or gas 20 burning installations that when combustion is first started in a cold furnace, incomplete, un- stable combustion occurs. An excessive air draft very easily extinguishes the flame by drawing it away from the burner nozzle. The burner con- 25 tinues for an interval to inject a larger or smaller amount of unburned combustible mixture into the furnace, so that when the ignition means again lights the flame the accumulated mixture burns suddenly, producing puffing, or at times 30 damaging explosions.

My invention avoids the above disadvantage by assuring the following procedure in lighting a burner of this type. First, the draft damper is opened part way to clear out any unburned gases 35 that may have accumulated in the furnace and duct system through leakage; when the damper reaches a predetermined partially open position, the burner is then lighted with only enough draft to prevent undue back pressure and smoky combustion, and finally, while the furnace and combustion chamber become hot enough to assure complete stable combustion, the damper or other draft control is swung gradually to its fully open 40 position for maximum draft and normal combustion. During the first portion of the burner starting cycle of shaft 8, the damper is rotated to its partially open position. During this gradual opening of the damper, the natural, induced, or forced draft of the heating system has a 45 chance to scavenge out any accumulated explosive mixtures which may have leaked into the furnace and flue system during the shut-down period. Then, with the damper partly open, the burner is started with the minimum necessary 50 draft, so that the cold combustible mixture will not be drawn away from the burner nozzle, extinguishing the flame. As the burner and furnace warm up, damper 4 is progressively opened 55 to its full extent gradually enough so that, when it reaches its open position and the control motor 60 9 stops, the furnace will be sufficiently hot for stable combustion.

When in response to the action of a thermostatic or manual switch motor control 9 is again energized it rotates the shaft clockwise one-hundred-eighty degrees farther, returning it and

the damper to their original positions. The hump on cam 10 is made long enough and is so positioned that as soon as rotation of shaft 8 commences, switch 12 is opened, turning off the burner 2. The damper 4 is gradually closed, requiring a time interval similar to that required for its opening position, say, thirty to sixty seconds. During this gradual closing of the damper the products of combustion and any unburned fuel and air which may have passed into the furnace after the burner was turned off are drawn into the stack 3 or moved out of the range of the burner flame when it is restarted on its next operating cycle. When motor 9 completes the half rotation of shaft 8 and cam 10, the damper 4 is restored to its closed position shown in broken lines in Fig. 3. During the period when the burner 2 is off the damper stays closed, preventing the circulation of cold air in response to natural draft and the consequent cooling of the furnace or oven. Thus a maximum of the stored heat is retained in the furnace and associated heat transfer system.

Various modifications in the details of the control system described may be made to adapt it to different heating systems and controls without departing from the spirit of the invention. While I have shown a stack damper for adjusting the draft, other means of varying the draft may be similarly governed and controlled. For example, a check-draft control damper, a draft damper at the combustion air inlet to the burner and furnace, or a power-driven fan or impeller for forced or induced draft, may be connected in known ways to the motor-driven timing device to co-ordinate the adjustment of the furnace draft and the starting of the fuel burner according to the operating cycle described above. 25 30 35

Having thus described my invention, what I claim and desire to secure by Letters Patent is:

1. In a heating system comprising a furnace, an automatic fuel burner, a stack leading from said furnace, and an adjustable draft damper in said stack, in combination, a motor-driven timing device arranged to control said burner and operatively connected to open and close said damper, said timing device operative to move said damper progressively from its closed to its open position and to put the burner into operation when a portion only of the opening movement of the damper has been completed. 50

2. In a combustion control system for a heating system comprising a furnace and an automatic fuel burner, in combination adjustable means for controlling the draft through said furnace and a motor-driven timing device operatively connected with said draft control means and said burner, said timing device operative when energized to first actuate said draft control means to cause a moderate flow of air through the furnace, next to put the burner into operation, and then to increase the draft through said furnace gradually to a maximum as the burner and furnace become warm. 55 60
